UNITED STATES PATENT OFFICE.

GEORGE W. GLASS, OF PIPER CITY, ILLINOIS.

APPARATUS FOR DUMPING THE GRATES OF RAILROAD-STOVES.

SPECIFICATION forming part of Letters Patent No. 373,732, dated November 22, 1887.

Application filed March 30, 1887. Serial No. 232,998. (No model.)

To all whom it may concern:

Be it known that I, GEORGE W. GLASS, of Piper City, in the county of Ford and State of Illinois, have invented certain new and useful 5 Improvements in Apparatus for Dumping the Grates of Railroad-Stoves; and I do hereby declare the following to be a full, clear, and exact description of the invention, such as will enable others skilled in the art to which it 10 pertains to make and use it, reference being had to the accompanying drawings, which form part of this specification.

My invention relates to an improvement in apparatus for dumping the grates of railroad-stoves; and it consists in the combination of a pivoted grate, of an endwise-moving rod which supports one side thereof, and operating rods or levers which cause the grate to dump in case of a collision or upsetting of the 20 cars, as will be more fully described herein-after.

The object of my invention is to connect the grate of the stove with a dumping mechanism which is operated by the collision or upsetting of the cars, so that in case of an accident all of the fire in the stove is instantly dumped through an opening in the bottom of the car directly upon the track, and thus avoiding all danger of the cars catching fire in 30 case of a wreck or the upsetting of the car.

Figure 1 is an inverted view of an apparatus embodying my invention. Fig. 2 is a side elevation of the same.

A represents the bottom of the car, which 35 has an opening through it just under the stove, and sufficiently large to allow all of the contents of the stove to be emptied through it directly upon the track in case of a collision or the upsetting of the car. The grate B is 40 hinged upon one side, and is designed to drop downward, so as to allow all of the contents of the stove to drop through the bottom of the car upon the track. The grate is connected, by suitable rods, with a door, I, which closes 45 the bottom of the opening through the car, and this door and the grate move together at all times. When the door and grate are in position, they are supported by a spring-catch, C, connected at its outer end to the lever D. 50 This lever is pivoted upon a suitable support upon the bottom of the car, and is connected at its outer end to the rear end of an endwise-moving rod or lever, G, which is connected at its outer end to the end of the car, or a bumper 55 rod or lever, H, which is fastened at one of

its ends to one corner of the car. This rod, lever, or bumper H is pivoted, hinged, or connected, in any suitable manner, directly to one end of the car and extends directly across the end of the car, as shown. That end which is 60 not connected directly to the end of the car, but is held at a slight distance in advance of it, will be struck by the end of the next adjoining car in case of a collision, and then the rod G will be forced endwise, so as to move 65 the inner end of the lever D in such a manner as to withdraw the catch or latch C from under the grate B, and thus allow the grate to drop downward and dump the fire upon the track, and thus prevent any possibility of the 70 car catching fire in case of a wreck. Whenever there is a wreck, one or both ends of the cars are staved in and the violent collision of the cars will always operate the lever H, and thus dump the fire upon the track before the 75 stove can be upset and set the car on fire. The stove used in connection with this dumping apparatus should be made of sheet-iron, so as to retain the heat as short a time as possible, and thus lessen the risk of the danger 80 of setting the car on fire should the stove be upset.

In order to cause the contents of the stove to be dumped upon the track in case the car should upset, there will be attached to the bottom of the car, on each side of the pivot of the lever D, a lever, J, which extends downward close to the ground, and which are so arranged that when the car is upset in either direction the end of one or both of these levers J will 85 touch the ground and cause the latch C to be operated, and thus dump the contents of the stove upon the track.

Having thus described my invention, I 95 claim—

The combination of the car having an opening through its bottom, and a door for closing this opening, and the stove-grate B, which is connected to the door so as to move therewith, the catch C, for supporting the door, the operating-lever D, which is connected to the catch C at its inner end, and the levers J, connected to the bottom of the car upon opposite sides of the lever D, substantially as described.

In testimony whereof I affix my signature in presence of two witnesses.

GEORGE W. GLASS.
